UNITED STATES PATENT OFFICE.

FRANK J. GOULD, OF SIDNEY, OHIO.

MAGAZINE-STOVE.

SPECIFICATION forming part of Letters Patent No. 247,633, dated September 27, 1881.

Application filed May 25, 1881. (Model.)

To all whom it may concern:

Be it known that I, FRANK J. GOULD, of Sidney, in the county of Shelby and State of Ohio, have invented a new and Improved Magazine 5 or Self-Feeding Stove or Furnace, of which the following is a specification.

The object of this invention is to provide a magazine stove or furnace that is less expensive to construct, has greater heating capacity, 10 is more economical of fuel, and is less liable to gas-explosions than other magazine-stoves now in use.

My improvements consist in constructing the magazine of the stove with a vertical row of 15 perforations opening outwardly into a tube attached to said magazine, closed at its upper extremity and open at its lower end, and near the latter communicating with the outside by means of a short tube passing through the side 20 of the stove; also, in providing the magazine at its top with an annular collar cut away upon the front; also, in the combination, with the shell, the top, and the collar cut away as aforesaid, of the magazine having its top situated at some distance from the top of the stove, 25 and the chamber formed between said magazine-top, collar, and stove-top; also, in various details of construction, all of which will be hereinafter more fully described.

30 In the accompanying drawings, Figure 1 is a sectional elevation of the stove on line *x x*, Fig. 2. Fig. 2 is a plan of the same, with the fixed cover removed. Fig. 3 is a reverse plan view of the magazine and that portion of the shell in which it is supported. Fig. 4 is a sectional elevation of a portion of the stove.

Similar letters of reference indicate corresponding parts.

In the drawings, A represents the base of 40 the stove, supported on legs *a a*; and B is the shell of the stove, resting thereon.

C is the grate, *b* the ash-pit, and C' the ash-pit door; and *c* represents the combustion-chamber.

45 D is the magazine, provided with radial semi-cylindrical ears *d*, that engage over and upon corresponding rods or lugs *f*, that project inward from the shell B, and thereby support said magazine D centrally within said shell B, so that the former may at any time

be removed from the shell B for repairs or renewal. Secured on the top of said magazine D, and at right angles to its axis, is a circular collar or annular plate, E, that extends nearly to the shell B, to direct the heat and products 55 of combustion over the top of the magazine D, excepting at the front, where it is cut away, as shown at *g*, to permit the heat and products of combustion to pass up. On this collar E are secured two parallel bars or guides, E', 60 between which slides the two-part magazine-cover F, that is operated by rods F², which extend outward through the shell, as shown, said cover F covering the opening F' in the top of the magazine D, through which the fuel 65 is introduced into the stove. The magazine D is provided on one side with a vertical row of holes or orifices, *h*, by means of which communication is held between the interior of said magazine D and a gas-consuming pipe or 70 chamber, G, that is secured to it over said holes *h*, said chamber G being open at the bottom for the admission of heat from the combustion-chamber *c*, and being provided near its bottom with a tube, *k*, extending laterally 75 through the shell B for the admission of the outer air, the purpose being to permit the gradual escape of the gases from the magazine D, so that they shall not explode therein, into the chamber G, where they may be inexplosively 80 consumed by admixture with the air admitted through the tube *k*.

H H represent the mica-glazed windows or openings in the side of the shell B. In some instances the shell B is made in two sections, 85 the upper one of which carries or supports the magazine D, and is fitted over the lower section, as shown in Fig. 1; but this style of construction is not essential, as the shell B may be constructed in one piece, if desirable. 90

I represents the stove-top, having a central feed-opening, *m*, closed with a cover, I', that may be either a swinging or lifting cover, as may be desired. K is the smoke-pipe, projecting upward from said cover I'. An open space 95 or chamber, M, is formed between the top of the magazine D and the cover I', for the free passage of the products of combustion from the combustion-chamber *c* to the exit-pipe *k*.

It will be seen that by having the magazine 100

D disconnected from the shell B all parts of the stove are exposed to the fire, whereby its radiating-surface is largely increased; that because of the perforations in the side of the 5 magazine the gases from the coal contained therein will escape into the stove and be burned, and will not escape into the room when the cover is removed for recharging the magazine with fuel; and with this construction the outer 10 air is prevented from entering the magazine to cause explosions of gas therein.

Having thus fully described my invention, I claim as new and desire to secure by Letters Patent—

15 1. The combination, with shell B and magazine D, having a vertical row of perforations, h, upon its front, of the tube G, closed at top and open at bottom, and connected with the outside air by means of pipe k, situated near 20 the lower end of said tube G, substantially as and for the purposes described.

2. The combination, with the shell B and magazine D, of the annular collar E, having its front cut away to form opening g, substantially as and for the purposes described. 25

3. The combination, with the shell B, the top I I', and the collar E, having front orifice, g, of the magazine D, whose top is some distance below the top I I', and the chamber M, substantially as described, whereby the top of 30 the stove is heated, as set forth.

4. The within-described stove, consisting of bottom A, shell B, top I I', removable, magazine D, provided with perforations h, pipe k, and tube G, annular collar E, double top F, 35 handles F², and flue K, substantially as and for the purposes described.

FRANK J. GOULD.
